UNITED STATES PATENT OFFICE.

EMIL H. W. ULLRICH, OF CHICAGO, ILLINOIS.

RECEPTACLE.

1,134,427.

Specification of Letters Patent. Patented Apr. 6, 1915.

Application filed April 9, 1914. Serial No. 830,577.

To all whom it may concern:

Be it known that I, EMIL H. W. ULLRICH, a citizen of the United States, and a resident of Chicago, in the county of Cook and State of Illinois, have invented certain new and useful Improvements in Receptacles, of which the following is a specification.

My invention relates to receptacles and involves improved application of covers thereto.

The invention concerns particularly sheet metal receptacles having sheet metal slip covers, that is, covers which merely slip over the receptacle mouth as distinguished from such covers as, for example, are screw threaded to the receptacle. It is very desirable in receptacles containing certain classes of goods that the covers engage accurately and with sealing fit to prevent spoiling or deterioration of the contents, and that the covers are locked against displacement or removal in order that the receptacles may be handled and shipped without danger of the covers coming off. It is also desirable, particularly where the goods in a receptacle are to be gradually drawn upon and used, that the cover may be applied in such manner as to seal the receptacle to prevent leakage of the contents, while at the same time to be readily removable and readily accurately replaced. For example, where receptacles contain coffee, tea, spices, and allied goods, it is desirable that the covers be adapted for sealing and interlocking engagement with the receptacles so that they can be stored as stock and readily shipped without danger of spoiling or leakage of the contents and without danger of the covers accidentally coming off. It is also desirable with this class of goods that the housewife, for example, may readily unlock and remove the cover and then be able to apply the cover so that while it will still seal the receptacle it can be more readily removed at any time that it is desired to draw on the contents. As another example, shoe-blacking receptacles may be cited. With this article it is very desirable that the receptacles be absolutely sealed to protect the contents and that the cover be locked against displacement when the receptacles are in stock or handled and shipped. On the other hand, it is very desirable, after the first unlocking and opening of the cover, that the cover can be applied and removed more readily while at the same time it will fully seal.

The above features are also desirable in receptacles for containing paints, varnishes, ink, soap, and in fact any material which should be sealed to be preserved and whose use from time to time necessitates repeated opening and closure of the containing receptacle.

The object of my invention is therefore to provide construction and arrangement for receptacles and covers which will cause the covers when applied with force to become locked against displacement and which will effectually seal the receptacle and protect its contents; and to provide such construction and arrangement which will enable the cover to be applied with less force in another position with reference to the receptacle in order that it may be more readily removed and replaced as the contents of the receptacle are drawn upon, while at the same time effectually sealing the receptacle after each application thereto.

More in detail, the invention involves the provision of beading or grooving on one part with corresponding grooving and beading on the other, the disposition being such that the grooving and beading will engage and interlock only after considerable force has been applied to the cover, while if only a slighter force is applied to the cover it will have a slip and sealing fit without interlocking and to be readily removed or applied.

The construction and arrangement together with its useful results will be clear from the following specification together with the accompanying sheet of drawings in which—

Figure 1 is an elevational view of a receptacle with part broken away to more clearly show the construction and arrangement, the cover being shown fully applied and locked. Fig. 2 is a similar view of the upper part of the receptacle showing the cover unlocked but still sealing the receptacle, Fig. 3 is a sectional view of the corner of a receptacle showing a modified arrangement, the cover being fully closed and locked, Fig. 4 is a similar view showing the cover partly unlocked, Fig. 5 is a sectional view of the corner of a receptacle showing the cover locked, Fig. 6 is a similar view showing the cover applied but unlocked, Fig. 7 is a similar view showing the cover inverted and sealing the receptacle, Fig. 8 is a perspective view of one half of the

upper part of a receptacle showing the invention applied to a polygonal receptacle, and Figs. 9 and 10 are sectional views of the upper corner of a receptacle showing other modified arrangements.

In Fig. 1 I have shown a receptacle comprising a cylindrical body 10, the base 11 and the cover 12. As shown, the body near its upper edge has the exterior annular groove 13 and the cover has in its flange 12' the internal annular-ridge or bead 14 for engaging in the groove 13 when the cover is fully applied, the cover being then locked in place. The cover is thus applied after a receptacle is filled in order that its contents will be protected when the receptacle is put in stock or shipped. Not only do the bead and groove interlock to hold the cover in place but a more effective barrier or seal is provided against leakage or against entrance of air. As special force is necessary to apply the cover in locking position it will also require extra force to unlock the cover. As shown, the usual external ridge or bead 15 is provided on the receptacle below the cover flange, in order that a suitable implement can be applied between this bead and the cover flange to pry the cover upwardly to effect disengagement of the locking bead and groove. To give better prying surface to the cover the flange end may be curled over as indicated at 16, such curling also greatly strengthening the cover. With this arrangement the cover can readily be unlocked by applying a screw driver or knife, or any other suitable implement or object between the bead 15 and the cover end 16, and after disengagement of the locking groove and bead the cover can be readily entirely withdrawn to open the receptacle. After the receptacle is thus opened and the intention is to draw on the contents from time to time, the cover need not be fully applied to interlocking position with the receptacle but need be slipped on to the receptacle only until the bead 14 reaches the upper edge of the body, the slip engagement of the section *a* of the flange with the sides of the body being then sufficient to effect sealing and to hold the cover in place under all ordinary conditions. The bead 14 forms an abutment for determining the distance of application of the cover, and engagement of the bead with the edge of the body 10 will also assist in sealing the receptacle. In order that the cover may be more readily applied the upper section 10' or the body 10 is deflected inwardly slightly as shown in Fig. 2, to form an inclined annular guide flange for the lower edge 16 of the cover. When the cover is then applied this edge 16 will be guided by the flange 10' into and centered with reference to the receptacle whereupon a slight pressure will carry the cover down until the bead 14 abuts against

the base of the flange 10'. If greater security of the cover is desired a little greater force may be applied and the cover pushed down further until its bead interlocks with the groove 13. It will be readily understood that the beading 14 may be continuous or sectional, that is, the bead may extend entirely around the cover or shorter beads may be provided at intervals for engaging with the continuous groove 13.

In Figs. 3 and 4 a modified arrangement is shown, the body 10 being provided with an additional groove 13' below the groove 13 and the cover being provided with additional beading 14' below the beading 14, the beading 14 and 14' interlocking with the grooving 13 and 13' respectively when the cover is fully applied to firmly lock the cover in place and increase the sealing efficiency. Fig. 4 shows the cover partly applied after unlocking, the upper beading 14 engaging the flange 10' at the edge of the body and the lower beading 14' interlocking with the upper groove 13. The lower beading 14' need not be as pronounced as the upper beading 14 in order that the cover can be readily removed by hand from the position shown in Fig. 4. Instead of applying the cover up to the top beading it could of course be applied only until the lower beading 14' reaches the flange 10' in which position the end of the cover flange below the beading 14' would have a slip and sealing fit with the receptacle body and the cover could very readily be removed when desired without the aid of any implement.

In Figs. 5, 6 and 7 another modified arrangement is shown, the construction of the body being the same as in Figs. 1 and 2 except that the upper part *e* thereof is curled inwardly to give the so-called "false wire" effect and to provide the cylindrical seat 17. The flange of the cover is the same as in Figs. 1 and 2 but the top of the cover is centrally deflected upwardly to form the dome 18, the cylindrical section 18' at the base of the dome being of external diameter to snugly fit the seat 17 when the cover is applied after inversion thereof, the flat peripheral section 19 of the cover surrounding the dome then engaging with the top of the body 10 as indicated in Fig. 7. With this arrangement when the cover is applied in the ordinary manner its flange 12' will slip fit the body 10 and when the beading 14 engages and interlocks with the groove 13 the cover will be securely locked to the receptacle with sealing fit as indicated in Fig. 5. After the cover has been forced open it may thereafter be applied only part way until the bead 14 abuts against the end of the body as shown in Fig. 6, or it may be inverted and applied with its dome inserted into the receptacle outlet and seating against the seat 17 as shown in Fig. 7. When the

cover is applied as shown either in Fig. 6 or Fig. 7, the receptacle is sealed but the cover can readily be withdrawn by hand and can readily be applied as the contents 5 of the receptacle are drawn upon. When the cover is inverted it forms a receptacle which can be used for measuring or other purposes. For example it could be used as a mixing receptacle by painters.

10 In Fig. 8 an arrangement is shown involving the features of my invention and which is particularly adaptable to receptacles of polygonal shape. In such receptacles, particularly where the sides are of 15 considerable length, the edges of the sides might buckle or bow when the cover is applied and the receptacle would not be sealed. To prevent this I preferably deflect the inner section 20 of the cover top downwardly 20 to produce the peripheral channels 21 as indicated in Fig. 8, which channels will intimately receive the upper ends of the sides of the body 10 when the cover is applied and will prevent buckling or bowing 25 of these ends. Fig. 8 clearly shows how the curled over or "false wire" ends e are intimately held in the channels. The channels could have the same curvature as the ends e to snugly fit throughout when the cover is 30 applied to thus give a very effective seal. When the cover is fully applied the bead 14 thereon will interlock with the groove 13 on the receptacle body and will securely hold the cover in place. When the cover is 35 unlocked and removed it can then be replaced only sufficiently to bring the beads 14 against the ends e and the slip fit of the cover flange below the beads will then effect sufficient sealing for ordinary purposes.

40 Fig. 9 shows the downwardly deflected type of cover applied to a body having its upper edge deflected to form the flange 10' as in Figs. 1 and 2. The channel sections 21 of the cover intimately receive the flange 45 sections 10' when the cover is fully applied and will prevent buckling or bowing in order to maintain a sealing fit between the cover flange sections and the side sections of the body 10.

50 Instead of having an external groove provided on the receptacle body and an internal bead on the cover flange, the body could have an external bead 22 and the cover an internal groove 23 as illustrated in Fig. 10. 55 When the cover is fully applied its groove would interlock with the body bead, and when the cover is partly applied the body bead would act as an abutment for the lower edge of the cover flange. It is also unnecessary to curl up or bead the lower edge of the cover flange, but this is desirable particularly in larger receptacles to stiffen and strengthen the cover flange and also to provide an abutment for an unlocking implement.

I do not of course desire to be limited to the exact forms and arrangements which I have shown and referred to as others might be possible which would still come within the scope of the invention, the main 70 object of which is to provide for a locked or permanent position of the cover and a free temporary position of the cover but with sealing engagement with either position.

I claim as follows:

1. In a receptacle, the combination of a container body and an external slip cover, the body having an annular external groove at the cover engaging section, and said cover having an internal bead adapted to engage 75 in and to interlock with said groove after the cover has been fully applied, said cover when partially applied having slip fit with the body above its groove and the cover bead then serving as an abutment to engage 80 85 with the upper edge of the body.

2. In a receptacle, the combination of a container body and an external slip cover, the cover comprising a top and side flange for receiving the upper end of the body, 90 said body at its cover engaging section having an external annular groove, said cover flange having an internal annular bead, the end of said flange below said bead being adapted for slip fit engagement with the 95 section of the body above its groove when the cover is partially applied and the upper edge of the body then forming an abutment for the cover bead, said cover bead and body groove entering into interlocking engagement when the cover is fully applied, the receptacle being sealed during either application of the cover.

3. In a receptacle, the combination of a body and a slip cover therefor, the body at 105 its upper edge being curled inwardly to form an internal seat, the cover receiving section of the body being externally grooved and the flange of the cover being internally beaded, such beading and grooving being 110 adapted for interlocking engagement only after the cover has been fully applied, the section of the cover flange below its beading being adapted for slip fit with the exterior of the body when the cover is partially applied and the upper edge of the body then acting as an abutment for the cover bead, the central portion of the cover top being deflected to form a peripheral seat 115 adapted for engaging said internal seat of the body when the cover has been fully applied.

4. In a receptacle, the combination of a body and a slip cover therefor, the body at its upper edge being curled inwardly to 120 form an internal seat, the cover receiving section of the body being externally grooved and the flange of the cover being internally beaded, such beading and grooving being 125 adapted for interlocking engagement only 130

4
after the cover has been fully applied, the section of the cover flange below its beading being adapted for slip fit with the exterior of the body when the cover is partially applied and the upper edge of the body then acting as an abutment for the cover bead; the central portion of the cover top being deflected upwardly to provide a peripheral seating area adapted for intimately engaging with said interior seat of

the body when the cover is inverted and applied with its deflected portion into the body mouth.

In witness whereof, I hereunto subscribe my name this 3d day of April, A. D. 1914. 15

EMIL H. W. ULLRICH.
